UNITED STATES PATENT OFFICE

WILLIAM J. HOY, OF ATLANTIC CITY, NEW JERSEY

DESIGN FOR A RADIO FOOTBALL CHART

Application filed September 2, 1931. Serial No. 40,984. Term of patent 3½ years.

To all whom it may concern:—

Be it known that I, WILLIAM J. Hoy, a citizen of the United States, residing at Atlantic City, in the county of Atlantic, State of New Jersey, have invented a new, original, and ornamental Design for Radio Football Charts, of which the following is a specification, reference being had to the accompanying drawing, forming part thereof.

The figure is a plan view of a radio football chart, showing my new design. The chart as illustrated has no appreciable third dimension.

I claim:—

The ornamental design for a radio football chart, as shown and described.

WILLIAM J. HOY.
